UNITED STATES PATENT OFFICE.

HARRY J. MELLON, OF PITTSBURGH, PENNSYLVANIA.

COMBINATION PEN AND PENCIL HOLDER AND CALENDAR.

Application filed February 24, 1921. Serial No. 447,380.

To all whom it may concern:

Be it known that I, HARRY J. MELLON, a citizen of the United States, residing at Pittsburgh, in the county of Allegheny and State of Pennsylvania, have invented certain new and useful Improvements in Combination Pen and Pencil Holders and Calendars, of which the following is a specification.

This invention relates to a combined pen or pencil holder and calendar, designed primarily as an improvement on the construction of a device of such type as set forth in Letters Patent No. 753,088, granted to me Feb. 23, 1904, and besides embodying the objects and advantages as set forth in said Letters Patent, has for its further object to provide the device, in a manner as herein-after set forth, with means which will overcome the necessity of entirely removing the sleeve, provided with indicia to designate the days of the month, from the holder element when desired to adjust the device relative to a change in dates or to ascertain a certain date, under such conditions providing a more convenient manner for adjusting purposes, as well as efficient one, and at the same time setting up an unusually neat and compact device.

Further objects of the invention are to provide a pen or pencil holder combined with a calendar which is simple in its construction and arrangement, accurate when operated, strong, durable, efficient in its use, readily set up, and comparatively inexpensive to manufacture.

With the foregoing and other objects in view the invention consists of the novel construction, combination and arrangement of parts, as hereinafter more specifically described, and illustrated in the accompanying drawings; wherein is shown an embodiment of the invention, but it is to be understood that changes, variations and modifications can be resorted to which come within the scope of the claims hereunto appended.

In the drawings wherein like reference characters denote corresponding parts throughout the several views:

Figure 1, is an elevation of a combined pen or pencil holder and calendar. 50

Figure 2, is an elevation of the holder element. 55

Figure 3, is a like view of the adjustable sleeve provided with indicia to designate the days of the week. 55

Figure 4, is a like view of the sleeve provided with indicia to designate the days of the months and the months of the year. 55

Figure 5, is an elevation of a combined pen holder and calendar with the cap for 60 the pen removed and the holder element removed.

The example of the device is shown in connection with a pen holder, but it is to be understood that the invention fully applies 65 to a pencil holder, either one combined with a calendar, and referring to the drawings in detail 1 denotes a tubular member, which is termed the body portion of the device, and is formed with an octagonal portion 2, a cylindrical portion 3 and threaded portion 4. The cylindrical portion 3 has secured thereto a sleeve 5 provided with indicia to designate the days of the month, as 70 at 6, and which is arranged in the form of a spiral so as to conform to the threads of the portion 4. The octagonal portion 2, has secured therewith or connected thereto, in any suitable manner a pen or pencil, as 75 shown a pen, as indicated at 7. 80

The device includes what may be termed a holder or retaining element, which is tubular and formed with a narrow octagonal portion 8, and cylindrical portions 9, 10 and 11, and which are of different diameters relative to each other. The cylindrical portions 9 and 10 are formed respectively with the longitudinally extending rectangular slots 12 and 13. The cylindrical portion 11 is inset, as at 14, to provide a lug which engages 90 in the threaded portion 4, and the said cylindrical portion 11, is furthermore provided with a circular opening 15. 85

The holding element snugly fits the tubular member 1, is mounted on the cylindrical 95 portion 3 and extends upon the threaded

portion 4 and with the inset 14 extended into the thread or spiral groove 16 of said portion 4, whereby when the holding element will be shifted longitudinally of the member 1, when the latter is revolved.

Interposed between the holding element and the member 1, and positioned to be enclosed by the cylindrical portions 9 and 10 of the holding element, is a sleeve 17, which 10 has one end engaged by the shoulder, formed between the cylindrical portions 10 and 11 of the holding element, so that when the holding element is shifted the sleeve 17 will be carried therewith. The sleeve 17 is 15 of two different diameters and the enlarged portion is indicia to designate the months of the year, as at 19, and that portion of smaller diameter is provided with indicia to indicate the number of days in a month, as at 20. The names of the months are adapted to register and be exposed through the slot 13, and the number of the days of the months are to be exposed through the opening 15 when a day indicating sleeve, to be presently 25 referred to is shifted clear of the holding element.

The day indicating sleeve, that is for indicating the names of the days of the week, is indicated at 21, and consists of a cylindrical portion 22, having suitable indicia, as at 23, to designate the names of the days of the week, a narrow octagonal portion 24, at the inner terminus of the portion 22, a flange 25, integral with one terminus of the portion 24, a tapering portion 26 projecting from the flange 25, and an octagonal portion 27, extended from the portion 26 and smaller than the portion 24. The flange 25 provides a finger piece 30 so that the sleeve 21 can be conveniently handled or adjusted when desired. The portions 22 and 24 of the sleeve 21 is normally interposed between the portions 8, 9 of the holding element, and the sleeve 35 17, and with the flange 25 abutting against the portion 8, of said element. The tapering portion 26, as well as the octagonal portion 27 is mounted on the portion 2 of the member 1. When the sleeve 21 is extended 40 into the holding element until the flange 25 abuts against the portion 8, of said element, the portions 8 and 24 associate to prevent the sleeve turning relative to the holding element, or the tubular member 1, turning 45 relatively to the sleeve 21 or to the holding element, due to the associating of the octagonal portion 27 with the portion 2 of the member 1. To permit of the member 1 and sleeve 21, being turned or revolved relatively to the holding element, so that the indicia, on the sleeve 21, that is desired exposed through the slot 12, the sleeve is shifted slightly so that the narrow portion 24 will be removed from the portion 8, whereby 50 65 the adjustment or turning movement of the

parts can be had. It does not necessitate the entire removal of the sleeve 21 from the holding element to enable adjustment, as the major portion of the sleeve 21 which extends into the holding element is cylindrical.

The days of the month are exposed through the opening 15, and the proper date is exposed by turning the member 1 to adjust the holding element longitudinally, due to the travel of the inset 14, in the thread 75 or groove 16. The adjustment however cannot be had until the narrow octagonal portions 8 and 24 are moved clear of each other, by slightly shifting the sleeve 21 out of the holding element.

The sleeve 21 constitutes a locking member or locking sleeve between it and the holding element, and between the body portion and holding element.

What I claim is:—

1. A device for the purpose set forth comprising a cylindrical body portion provided with indicia and further having a part thereof polygonal and a part formed with a spiral groove, a rotatable and longitudinally shiftable retaining element mounted on and having means travelling in said groove to shift said elements and further having a narrow polygonal shaped portion at one end, and further having a pair of slots and an opening, a sleeve mounted on said body portion and having indicia visible through one of said slots, and a locking sleeve for said element, said sleeve having indicia visible through the other of said slots and having a cylindrical portion extending into said element and further having at one terminus of 95 said cylindrical portion a narrow polygonal shaped portion associated with the polygonal shaped portion of said element to prevent rotative movement of the element relative to the sleeve until the polygonal shaped part of the sleeve is cleared of the polygonal shaped portion of said element without withdrawing the entire sleeve from said element, said locking sleeve further having an additional polygonal shaped portion associated with the polygonal part of said body portion, and said indicia on the body portion visible through said opening.

2. A device for the purpose set forth comprising a cylindrical body portion provided with indicia and further having a part thereof polygonal and a part formed with a spiral groove, a rotatable and longitudinally shiftable retaining element mounted on and having means travelling in said groove to shift said elements and further having a narrow polygonal shaped portion at one end, and further having a pair of slots and an opening, a sleeve mounted on said body portion and having indicia visible through one of said slots, and a locking sleeve for said element, said sleeve having indicia visible through the other of said 130

slots and having a cylindrical portion extending into said element and further having at one terminus of said cylindrical portion a narrow polygonal shaped portion associated with the polygonal shaped portion of said element to prevent rotative movement of the element relative to the sleeve until the polygonal shaped part of the sleeve is cleared of the polygonal shaped portion of said element without withdrawing the entire sleeve

from said element, said locking sleeve further having an additional polygonal shaped portion associated with the polygonal part of said body portion, said indicia on the body portion visible through said opening, 15 and said locking sleeve having a flange constituting a finger piece.

In testimony whereof I affix my signature.

HARRY J. MELLON.
